UNITED STATES PATENT OFFICE.

EDWARD JOHN DOBBINS, OF WESTMINSTER, LONDON, ENGLAND.

DESIGN FOR PLATE-GLASS.

44,435.

Specification for Design.

Patented Aug. 5, 1913.

Application filed December 7, 1912. Serial No. 735,532. Term of patent 14 years.

To all whom it may concern:

Be it known that I, EDWARD JOHN DOBBINS, a citizen of the United States, residing at 28 Victoria street, Westminster, London, S. W., England, have invented a new, original, and ornamental Design for Plate-Glass, of which the following is a specification, reference being had to the accompanying drawing, forming part thereof.

Figure 1 is an elevation of a piece of plate glass showing my new design; Fig. 2 is an end edge view, looking in the direction of the arrow 2, and Fig. 3 is a side edge view looking in the direction of the arrow 3.

The letter *a* designates the notches in the Figs. 1 and 3.

I claim:

The ornamental design for plate glass as shown.

In testimony whereof I have hereunto set my hand in presence of two subscribing witnesses.

EDWARD JOHN DOBBINS.

Witnesses:

WILLIAM J. BOWKER,
REGINALD G. HARLOW.
